(57) **CLAIM**

The ornamental design for a portable charger device, substantially as shown and described.

DESCRIPTION

FIG. 1 is a top perspective view of a portable charger device showing our new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a back view thereof.

The broken lines shown in the drawings are for the purpose of illustrating portions of the portable charger device which form no part of the claimed design.
